OPHTHALMIC INSTRUMENT ARM

John H. Beverage, Eggertsville, N.Y., assignor to American Optical Corporation, Southbridge, Mass.

Filed Aug. 27, 1973, Ser. No. 391,704

Term of patent 14 years

Int. Cl. D24—01

U.S. Cl. D57—1 E

FIG. 1

FIG. 2

FIG. 3

FIG. 1 is a prospective view of the ophthalmic instrument arm of my design;

FIG. 2 is a rear view of the instrument arm; and

FIG. 3 is a front prospective view of the instrument arm showing the two portions in a space related position to one another.

I claim:

The ornamental design for an ophthalmic instrument arm, as shown and described.
